Primary Examiner — Zenia Bennett*(74) Attorney, Agent, or Firm* — Faegre Baker Daniels LLP(57) **CLAIM**

I claim the ornamental design for the flotation device, as shown and described.

DESCRIPTION

FIG. 1 is a perspective view of a flotation device of the present application, including a plurality of flotation members coupled to a flotation hub;

FIG. 2 is a top view of the flotation device of FIG. 1;

FIG. 3 is a bottom view of the flotation device of FIG. 1; and,

FIG. 4 is a corner view of the flotation device of FIG. 1. The broken lines show portions of the flotation device that form no part of the claimed design.

1 Claim, 4 Drawing Sheets(56)
